TALKING PICTURE VEHICLE

Filed April 1, 1929

Fig. 1.

UNITED STATES PATENT OFFICE

FREEMAN H. OWENS, OF NEW YORK, N. Y., ASSIGNOR TO OWENS DEVELOPMENT CORPORATION, OF NEW YORK, N. Y., A CORPORATION OF NEW YORK

TALKING PICTURE VEHICLE

Application filed April 1, 1929. Serial No. 351,745.

This invention relates to improvements in talking picture vehicles, the object of the invention being to provide a portable talking picture apparatus which is well adapted for advertising purposes.

With the foregoing and other objects in view, the invention consists in the novel combination of elements which will be more fully described hereinafter and particularly 10 pointed out in the claims.

In the drawings accompanying and forming part of this specification,

Fig. 1 is a plan view of a vehicle embodying the features of the present invention, the 15 top of the vehicle being broken away to disclose the arrangement of the apparatus within the vehicle, the dotted lines indicating the position of the loud speakers when the vehicle doors are closed; and

Fig. 2 is a rear elevation of the vehicle shown in Fig. 1.

The same characters of reference designate the same parts in the different figures of the drawings.

Referring to the drawings, 1 designates the 20 body of a suitable truck or motor vehicle mounted on wheels 1^a, within which vehicle body is mounted a projector 2 equipped with a sound reproducing attachment 3 suitably connected with an amplifier 4; the latter being connected with a plurality of loud speakers 5 preferably mounted on the swinging rear doors 6 of the vehicle, so that when the doors 6 are open the loud speakers will 25 be presented outwardly in the full line position shown in Fig. 1. The projector and other sound-reproducing apparatus are illustrated only conventionally herein, since these devices are well known and it is deemed unnecessary to describe them in detail.

The doors 6 of the vehicle are provided at their outer edges near the upper ends thereof with suitable brackets 7 for engagement by a removable rod 8 which serves not 30 only to hold the doors open, but also acts as a support for a roller or other suitable type of screen 9 on which the pictures 10 projected from the apparatus 2 may be displayed, the width of the screen being such 35 that when the doors are open the loud speak-

ers are fully exposed at the opposite vertical edges of the screen, as clearly shown in Fig. 2.

The bottom of the screen 9 is also provided with a rod 8^a, which serves to hold the screen flat when in unrolled position, and which is also engageable with brackets 7^a at the lower portion of the doors, thus holding the screen unrolled and serving as an additional brace for the open doors.

The apparatus above described is well adapted for advertising talking pictures, patent medicines or any other merchandise in connection with which it is desired to present pictures accompanied by sales talk as to the merits of the articles advertised, or by music. For operation, the vehicle is driven to a place where it is likely to attract attention, whereupon the rear doors are thrown open thus presenting the loud speakers toward the expected audience, and the screen-carrying rod 8 placed in position in its brackets 7, thus serving to hold the doors open. The screen is then unrolled so as to cover the door opening and the rod 8^a engaged with the brackets 7^a, whereupon the operator actuates the projecting apparatus and its associated sound-reproducing attachment, thus producing the desired pictures and spoken words or music synchronously. When it is desired to move to another location, the screen is rolled up, removed from its brackets and stored away inside the vehicle body, whereupon the doors may be closed, the loud speakers being thus brought to the dotted line position shown in Fig. 1.

From the foregoing it will be seen that I have provided a very compact apparatus by means of which advertising matter comprising pictures and spoken words or music may be advantageously exhibited and which can at a moment's notice be set in operation and as quickly closed, whereby the exhibition can be displayed at locations far apart within a comparatively short space of time.

Having thus described my invention, what I claim is:

1. A portable talking picture apparatus, comprising a vehicle having swinging doors, a projector and sound-reproducing device

mounted in said vehicle, a plurality of loud speakers mounted on said doors in position to face outward when the doors are open, and removable means for supporting a screen between said open doors and effective to retain said doors in open position.

2. A portable talking picture apparatus, comprising a vehicle having swinging doors, a projector and sound-reproducing device
- 10 mounted in said vehicle, a plurality of loud speakers mounted on each of said doors in position to face outward when the doors are open and to be enclosed within the vehicle when the doors are closed, and removable
- 15 means for supporting a screen between said open doors and effective to retain said doors in open position.

3. A portable talking picture apparatus, comprising a vehicle having swinging doors,
- 20 a projector and sound-reproducing device mounted in said vehicle, a plurality of loud speakers mounted on each of said doors in position to face outward when the doors are open and to be enclosed within the vehicle
- 25 when the doors are closed, means for supporting a screen between said open doors, and means for retaining said screen in flat condition.

4. A portable talking picture apparatus, comprising a vehicle having swinging doors, a projector and sound-reproducing device mounted in said vehicle, a plurality of loud speakers mounted on each of said doors in position to face outward when the doors are open and to be enclosed within the vehicle when the doors are closed, brackets carried by the doors near their upper and lower ends, and rods removably supported in said brackets for supporting and retaining a screen in flat condition between the open doors, said rods being effective to maintain the doors in open position.

In testimony whereof, I affix my signature.

FREEMAN H. OWENS.
